UNITED STATES PATENT OFFICE.

BENJAMIN FRANKLIN SPARKS, OF HUNTINGTON, WEST VIRGINIA, ASSIGNOR OF THREE-EIGHTHS TO WILLIAM RICHARD POWELL AND THREE-EIGHTHS TO LLOYD CLARANCE LOWE, BOTH OF HUNTINGTON, WEST VIRGINIA.

INTERNAL-COMBUSTION ENGINE.

1,184,495.

Specification of Letters Patent. Patented May 23, 1916.

Application filed July 21, 1915. Serial No. 41,125.

To all whom it may concern:

Be it known that I, BENJAMIN F. SPARKS, a citizen of the United States, residing at Huntington, in the county of Cabell and State of West Virginia, have invented a certain new and useful Improvement in Internal-Combustion Engines, of which the following is a specification.

My invention relates to valves of the rotary sleeve type for internal combustion engines and consists in the construction and combinations of parts described and claimed.

The principal object of my invention is to provide an internal combustion engine having a rotary sleeve valve which is to be fitted into the bore of the explosive motor and the valve in its turn acts as the cylinder or bore in which the working piston operates.

Another object is to produce a valve of simple construction which may be embodied in engines as in present use without altering the design thereof.

Another object is to provide a valve which has special provision for uniform lubrication. By reason of this provision an even wearing of the parts is accomplished.

A further object is to provide an engine cylinder especially adapted to this particular valve. By this special construction of cylinder, a tight explosion chamber is formed from which leakage of the gases is reduced to a minimum.

With other objects in view which are hereinafter described and specifically pointed out in the appended claims, reference is now directed to the accompanying drawings, in which—

Figure 1 is a vertical section through the device on line 1—1 on Fig. 2. Fig. 2 is a cross section on line 2—2 on Fig. 1. Fig. 3 is a detail elevation of the rotary sleeve valve. Fig. 4 is a detail cross section on line 4—4 on Fig. 1. Figs. 5 to 8 inclusive are diagrammatic sectional views illustrating the positions of the valve during one complete cycle of operation of the engine. Fig. 9 is an inverted plan view of the valve holding ring hereinafter referred to. Fig. 10 is a detail section on line 10—10 on Fig. 1.

The engine shown is of the 4 cycle type and may have as many cylinders as practice requires, but for facility of description I

have shown only one cylinder it being obvious that the description of one will suffice for the others.

Mounted on the base or casing 1, and in suitable bearings thereon, is the main or crank shaft 2 the shaft being formed with a crank 3. To the wrist pin of the crank 3 is joined the connecting rod 4 which is in turn connected to the wrist pin 5 of the piston 6. The wrist pin 5 extends to the periphery of the piston 6 at both sides and has an axial bore 7 into which oil is fed in a manner hereinafter to be explained. The bore 7 has a transverse oil passage 8 as indicated in dotted lines in Fig. 1 which leads to the bearing surface between the connecting rod 7 and wrist pin 5. The piston 6 is provided with the usual packing rings as shown in Fig. 1.

Mounted over a central opening in the top of the casing 1 and secured to the casing by bolted flanges 9, is a cylinder 10. The cylinder 10 is suitably water-jacketed as at 11 and has a central bore 12 in which the rotary sleeve valve 14, is mounted. The head of the cylinder 10 has an inward extension 13 between which and the top of the piston 6, the explosion cylinder of the engine is formed. The inward extension 13 is rounded upwardly to its circumferential radius between which and the bore 12 of the cylinder, a pocket 15 is thus formed wherein the valve 14 is adapted to closely fit. A leak-proof joint is thus produced which will prevent the escape of the gases from within the explosion chamber.

The water jacket 11 of the cylinder 10 is apertured near the bottom to receive water inlet pipes 16 and also apertured at the top to receive water outlet pipes 17, one of each of these pipes is provided at diametrically opposite places as shown in Fig. 1. The purpose of this arrangement is to cause a symmetrical flow of water through the jacket 11 and thus the excessive heat from the cylinder 10 is carried away in a uniform manner as shown by the arrows in Fig. 1. The face of the bore 12 of the cylinder 10 is grooved at one side as at 18 to form an oil passage which communicates at the top with a lateral duct 19 in the cylinder wall. The duct 19 is piped up to a similar duct 20 also in the cylinder wall by a short pipe 21. Arranged in the same plane with the duct

20 is another duct 22. These ducts 20 and 22 are connected at their inner ends and thus provide an opening in the wall of the cylinder and by this means a constant supply 5 of oil to the bore 12 and to the face of the valve 14 is insured. An oil cup 23 is connected to the oil duct 22 and constitutes the oil supply for the valve 14, bore 12, piston 6 and wrist pin 5.

10 In order to lubricate the surface of the piston 6, the valve 14 is apertured with a plurality of oil openings 24 near the bottom. These openings register at times with the oil groove 18 and when in such register, oil 15 flows through the openings 24 into the bore of the valve 14 and is in turn taken up by the reciprocating piston 6. The oil will gradually work upwardly and cover the entire surfaces of the frictional parts. Some 20 of the oil on the surface of the bore 14 will be collected by the edges of the bore 7 in the wrist pin 5 as the piston travels up and down and the oil thus collected will gradually fill the bore 7 and furnish lubricant to 25 the connecting rod bearing head as before explained.

Formed on the bottom of the rotary sleeve valve is a gear 25 which meshes with a worm 26 fixed on a longitudinally extended shaft 30 27 which shaft is mounted in suitable bearings in the casing as shown in Fig. 4. The shaft 27 has a sprocket wheel 28 on its end and a similar sprocket 29 is mounted on the crank shaft 2. A chain 30 travels over both 35 of these sprockets and serves to drive the shaft 27 and rotate the valve 14.

Cast integrally with the valve 14 and adjacent the gear 25, is an annular flange 31. The flange 31 fits closely in the opening in 40 the top of the casing 1 and by its means the valve is held in place. The upper side of flange 31 contacts with the cylinder flange 9 and is engaged by a two-part ring 32 at the under side as shown in Fig. 1. The ring 45 32 is made in two parts so that it can be fitted around the body of the valve 14 between the flange 31 and the base of the gear 25 and a part of each of the abutting edges of the ring is cut away at one side. 50 This is done to permit access of the pinion 26 to the gear 25 as shown. Suitable screw holes are provided in the ring 32 so that it may be fastened into place and form a thrust bearing base for the valve 14 which 55 rests thereon through the flange 31. The holding ring 32 is received in grooves 38, see Fig. 2. A portion of the top of the casing 1 is cut away adjacent the pinion 26 and sprocket 28 so as to accommodate these 60 parts when the device is assembled. The opening referred to, is closed by a cover plate 33 as shown in Fig. 1.

By reference to Fig. 2, it will be seen that the cylinder 10 is provided with intake and 65 exhaust ports 34 and 35 which are arranged

in the same horizontal plane. These ports establish communication between the explosion chamber of the engine and the intake and exhaust manifolds 36 and 37 at certain times. Such communication is cut off by 70 the wall of the interposed valve 14. The valve 14 is provided with a single port 39 which is adapted to register at times with the ports 34 and 35 thus establishing communication between these ports and the explosion chamber. This port 39 therefore 75 performs the dual functions of inlet and exhaust port for the explosion chamber and is brought into registration with the ports 34 and 35 as stated above, at the proper time 80 when the piston 6 is traveling its intake and exhaust strokes, by the rotation of the valve 14. By reason of the rotation of the valve 14 in a horizontal plane while the piston 6 travels vertically, the contacting 85 surfaces of the piston 6 and bore of valve 14, are constantly changed. Therefore, should foreign matter become lodged between the piston and the valve, there will be no danger of the wearing of vertical grooves in the surface of the bore of the valve causing a means for gas leakage. A spark plug 40 is screwed into an opening in the head of the cylinder 10 and serves to ignite the explosive mixture 90 when compressed by the piston.

Operation: From the foregoing description of the various parts of the device the operation thereby may be readily understood. Attention is now directed to Figs. 1, 2, 5, 6, 7 and 8 which illustrate the positions of the port 39 of the rotary sleeve valve 14 during one complete cycle of operation of the engine or during two revolutions of the crank shaft. The diagrammatical views Figs. 5 to 8 are composite views, 100 the upper portion being a cross section through the ports 34 and 35 and valve 14, while the lower portion of each view is a vertical section the two parts of the views being joined by a dot and dash line and intended to be read together. In Fig. 1 the piston 6 is at the top of its stroke and is just about to descend, the crank 3 turning in a clock-wise direction. When the piston is in this position the port 39 in the valve 110 14 is just midway of the exhaust shown in Fig. 2, but as the piston descends the valve 14 is turned so as to gradually register the valve port 39 with the intake port 34 so as to admit the new charge which is being 115 drawn in by the suction caused by the piston. When the piston has traveled one-half of its suction or downstroke as shown in full lines in Fig. 5, then the port 39 will have reached a position central of the intake port 34 and in continuing its rotation 120 in the direction of the arrow the port 39 is gradually moved out of registration with port 34 until at the time that the piston 6 reaches the bottom of its stroke as shown 125 130

in dotted lines Fig. 5, the intake port will be closed. In traveling from the last named position to that shown in Fig. 6, the piston has compressed the charge just taken in, and it is about to be ignited. At this time the valve port 39 has reached a position diametrically opposite to where it was in Fig. 2 and being adjacent a solid wall, the possibility of some of the force of the explosion being lost through the port 39 is entirely obviated. Fig. 7 shows the position of the parts when the piston has traveled its working stroke at which time the piston is at the bottom and about to ascend and since both intake and exhaust ports are securely covered during this last named stroke by the wall of the rotary sleeve valve, none of the expansive force of the exploded charge has become lost and consequently was wholly extended in driving the piston downwardly. At this time the port 39 in the valve 14 has just reached the edge of the exhaust port 35 which, upon continued movement of the parts, will gradually open. Now as the piston travels upwardly as in Fig. 8 the residue of the burnt charge is expelled until the piston reaches the top of its stroke when a complete cycle such as just described, is repeated.

30 I claim:—

1. In combination with the cylinder of an engine having a bore, a rotary valve mounted in said bore, an annular flange integrally formed on the valve near the bottom thereof, a gear formed on the valve at the bottom thereof but spaced from the aforesaid flange, and a holding ring situated in the space between the flange and gear for retaining the valve in its position, said ring comprising two parts and means for holding the ring to the casing, the abutting edges of said ring being partly cut away at one side.

2. In combination with the cylinder of an engine having a bore, a rotary valve mounted of the cylinder, a longitudinal groove in the wall of the cylinder adjacent to the bore and communicating with said oil duct, a rotary valve mounted in the bore of said cylinder, said valve having intermittently

coinciding openings with the groove in the bore and an oil supply communicating with said oil ducts.

3. In combination with the cylinder of an engine having a bore, a plurality of oil ducts in the wall of the cylinder, said bore being vertically grooved at one side and having communication with one of several transverse oil ducts, a rotary valve mounted in the bore of said cylinder said valve having a series of oil openings near its bottom edge which openings intermittently register with the vertical groove as the valve rotates, and an oil supply connected to one of the aforesaid oil ducts.

4. In combination with the cylinder of an engine having a bore, said bore having a vertical oil groove at one side, a plurality of oil ducts arranged in two horizontal planes and penetrating the cylinder wall, the bottom one of said ducts communicating with the oil groove, a pipe connecting the last named duct with a duct in a higher plane, an oil supply piped to the second duct in the higher plane, and another duct connecting the two last named ducts and being in open communication with the bore of the cylinder.

5. In an internal combustion engine, an engine base having a central opening in its top, a cylinder having a bore mounted over said opening, a hollow rotary valve mounted in the cylinder bore, said valve having a gear at the bottom thereof, means on the engine base in proximity to the opening for retaining the valve in position, a crank shaft and a gear shaft mounted on the engine base, sprockets connected by a chain, mounted on the crank and gear shafts, a pinion mounted on the gear shaft adjacent the sprocket and meshing with the gear on the valve, and a cover plate for an opening in the base through which the sprocket and pinion on the gear shafts project.
